UNITED STATES PATENT OFFICE.

RUTH G. SODERBERG, OF GRAND MARAIS, MINNESOTA.

BOOK CONSTRUCTION.

1,387,206.

Specification of Letters Patent. Patented Aug. 9, 1921.

Application filed November 9, 1916. Serial No. 130,435.

To all whom it may concern:

Be it known that I, RUTH G. SODERBERG, a citizen of the United States, residing at Grand Marais, in the county of Cook and

5 State of Minnesota, have invented certain useful Improvements in Book Constructions, of which the following is a specification, reference being had therein to the accompanying drawing.

10 The invention relates to a book construction, and more particularly to the class of stamp books.

The primary object of the invention is the provision of a book of this character wherein 15 the pages thereof support in a smooth manner sheets of postage stamps so as to hold the sheets smooth and to keep them from becoming mutilated or bent as well as obviating the sticking together of the stamps, 20 thereby permitting the convenient handling of the stamps in this manner at postoffices or other places for the distribution of the same.

Another object of the invention is the provision of a stamp book of this character 25 wherein the pages may be waxed or otherwise surfaced and the sheets of stamps held upon the pages so that the stamps, either singly or in number, can be conveniently 30 removed from the sheet which will be sustained smooth upon the page on one or both sides thereof, the pages of the book being suitably tabbed to enable access to different denominations of stamps in sheet 35 form with despatch when the book is in use.

A further object of the invention is the provision of a book of this character wherein the construction thereof is novel in form and will properly fasten stamps in sheet form. 40 memorandum slips or the like so as to hold the same in convenient access and in proper order without the folding of the sheets, the wrinkling thereof or otherwise bending so that they will be in smooth condition when 45 held upon the pages of the book.

A still further object of the invention is the provision of a book of this character which is simple in construction, thoroughly reliable and efficient in its purpose and inexpensive in manufacture.

Other objects will be in part obvious and in part hereinafter set forth.

50 The invention accordingly consists in the features of construction, combination of elements and arrangement of parts which will be exemplified in the construction herein-

after described, and the scope of the application of which will be indicated in the appended claim.

In the accompanying drawings:

Figure 1 is a perspective view of a book constructed in accordance with the invention showing the front cover open;

Fig. 2 is a sectional view on the line 2—2 of Fig. 1.

Similar reference characters indicate corresponding parts throughout the several views of the drawing.

Referring to the drawing in detail, A and B designate the cover sections, respectively, 70 and C the back to which are flexibly connected the cover sections in any ordinary well known manner, the cover sections being preferably made from stiff cardboard, although the same may be made from any 75 other suitable material, and flexible if desired throughout the extent thereof. Arranged between the cover sections is a plurality of leaves or pages D which are also made from cardboard, although they can be 80 made from any other suitable material, and the faces of these pages may be waxed or not as desired. Also it is to be understood that the size of the book can be varied and may contain any number of pages, as the occasion 85 may require. The plurality of pages are cut or otherwise provided with indexing tabs E, in which is arranged indicia indicative of the respective page contents so that at a glance a user can determine the desired page 90 for access thereto with despatch, the tabs E being projected from the pages so that the same can be clearly visible either before or subsequent to the swinging of the front cover section to open position. The arrangement and the protruding of the index tabs E and the construction of the cover section of the book may be varied, as may be desired.

The pages D are fastened between the cover sections A and B to the back C in any 100 suitable manner so as to be freely flexible and to accommodate between the pages certain matter without possibility of the bulging of the book when closed or the undue distortion of the pages when the book is in 105 use. Upon the inner face of the front cover section A at opposite points contiguous to the inner and outer side edges are resilient clips, each formed with a base 5 and a finger or tongue 6, the base 5 being of considerably greater width than the finger or tongue 6, and the said base is riveted or

otherwise fastened to the cover section A so that in the use of the clips the resilient tongues or fingers 6 will grip a sheet 7 to hold the same smooth and in place upon the 5 inner face of the cover A, and this sheet can be written upon or otherwise marked to serve as a memorandum in the use of the book when placing stamps in sheet form, slips or other memorandum sheets within 10 the book or the removal thereof therefrom.

On one or both faces of each page D is mounted a spring clip which comprises the relatively wider end portions 8 and 9 respectively and the intermediate narrow portion 15 10, the portion 8 being adjustably or otherwise fastened to the page contiguous to the line of hinge or flexing point thereof, preferably through the medium of screws 11, while the remaining portions 9 and 10 of 20 the clip are free and possess the required resiliency so that sheets of stamps, slips or memorandum sheets can be placed upon the face of the page and engaged by the clip for holding the sheet or slip smooth to 25 prevent the wrinkling or bending thereof when held in place within the book, yet the said sheets or slips are freely accessible so that when holding stamps in sheet form the said stamps can be singly removed or any 30 number of stamps detached from the sheet and likewise the slips can be detached from the clips for the removal thereof.

Each clip at the wider end 9 is bent outwardly along the straight edge thereof for a 35 distance between a predetermined extent to form a lip 12 slightly offset with respect to the plane of the clip so that it can readily be raised from the page by hand without disturbing the sheet or slip held by the clip 40 so that the sheet or slip can be removed or inserted between the clip and the face of the page adjacent thereto when the sheet or slip is to be held thereon. It is to be understood that either one or 45 more clips can be fastened to the page on each side thereof, as the occasion may require. One of the salient features of the invention is the formation of the clip upon the page so that the sheet or slip will 50 be held smooth to avoid wrinkling or bend-

ing thereof, and that such sheet or slip is readily accessible when the book is in use. The screws 11 permit the adjustment of the clips 10 relative to the faces of the page D on which the same are mounted so as to 55 accommodate variable thicknesses of sheets placed upon the pages and held by the clips. It is to be understood that the clips may be riveted or otherwise fastened to the page D, or adjustably fastened, and that the shape 60 of the clips can be varied, if desired.

In constructing the book, changes, variations and modifications may be resorted to such as come properly within the scope of the appended claim without departing from 65 the spirit of the invention or sacrificing any of its advantages.

From the foregoing description, taken in connection with the accompanying drawing, the construction and manner of use of the 70 herein described book construction is readily apparent and, therefore, a further explanation has been omitted.

Having thus described my invention, I 75 claim:

In a device of the kind described, a series of pages, a series of resilient clips arranged in pairs with the two of each pair positioned against the opposite sides of each page, the inner end of said clips being secured to each 80 page and their outer ends being free and formed with an outwardly curved lip disposed substantially at a right angle to the clip, the lips of facing clips on adjacent pages abutting each other to space adjacent 85 pages from each other, and a flexible binding strip having its opposite marginal portions secured to the two outer of the series of pages, the said strip being formed with a plurality of folds so arranged that the several pages are secured between them in a manner to permit the pages to be swung apart or against each other, the folds intervening between the pages forming means to space the pages apart, whereby open 90 ended compartments are provided by the said folds and the abutting lips of said 95 clips.

In testimony whereof I affix my signature.

RUTH G. SODERBERG.
